UNITED STATES PATENT OFFICE.

CHARLES ARTHUR BALDWIN, OF LOS ANGELES, CALIFORNIA.

APPARATUS FOR SPREADING LIQUID ASPHALT.

No. 927,315.

Specification of Letters Patent.

Patented July 6, 1909.

Application filed December 27, 1907. Serial No. 408,325.

To all whom it may concern:

Be it known that I, CHARLES A. BALDWIN, a citizen of the United States, residing at Los Angeles, in the county of Los Angeles and State of California, have invented a new and useful Apparatus for Spreading Liquid Asphalt and the Like on Roads, Courts, and the Like, of which the following is a specification.

10 This apparatus is designed for use in constructing what is known as oiled roads, and is more particularly adapted for distributing heavy liquids evenly over a surface in small or large quantities as may be desired.

15 The best material for constructing what is known as oiled roads is asphalt distributed on the surface in a liquid condition, which condition is only maintained when the asphalt is highly heated.

20 An object of the invention is to provide means whereby such highly-heated asphalt may be applied with the greatest ease, economy and comfort, to the surface to be treated.

25 A further object of the invention is to provide a liquid-distributing attachment for tank-wagons, by which the liquid can be applied to the surface in the most direct manner without liability of splattering or splash-

30 ing, and also to make provision whereby the distributing device can be raised when advisable, to avoid striking obstacles or to avoid engagement with the ground when passing over muddy or boggy roads or

35 streets.

An object of the invention is to provide means that are adjustable for the purpose of applying a more or less limited amount of the liquid material to the surface to be treat-

40 ed, and to completely cover the surface evenly regardless of the size of the stream and the amount of material delivered to such surface.

An object is to provide an oil distributer in 45 which the weight of the heavy liquid will tend to hold the valve closed when shut, and from which the oil will be drawn downward by hydraulic pressure from the tank so as to be forced into the loose earth to be impregnated with the oil.

Another object is to avoid the use of any leather or other soft packings or gaskets and yet to allow adjustment of the distributer toward and from the surface to be oiled.

55 The invention includes a heat-insulating tank and adjustable means for applying the

contents thereof to the surface to be treated, and embraces the various parts and combinations of parts hereinafter more particularly described and claimed. 60

Other objects and advantages may appear from the subjoined detailed description.

The accompanying drawings illustrate the invention.

Figure 1 is a rear perspective view of apparatus embodying the invention. The front of the tank and portions of the truck therefor are omitted from the view. The distributer is shown elevated for travel. Fig. 2 is a sectional elevation of the distributer lowered and in use on line indicated by x^2-x^3 , Figs. 4, 9 and 10. Fig. 3 is an enlarged detail on said line x^2-x^3 , of the rotary distributer-valve closed. Fig. 4 is a rear elevation of the distributer broken to expose 70 interior construction. Portions of the operating levers and the feeders are shown. Fig. 5 is a section on line indicated by x^5-x^6 , Figs. 4, 9 and 10. Fig. 6 is a section on line indicated by x^6-x^8 , Figs. 4, 9 and 10. Figs. 80 7 and 8 are fragmental bottom and top views respectively of the rotary valve, the outer shell of which is shown in longitudinal section in each of these views. Fig. 9 is a bottom view of the distributer, portions being 85 broken away to expose parts that would otherwise be hidden. Fig. 10 is a broken plan or top view of the valve and its hangers detached from the distributer pipe. Fig. 11 is a fragmental, sectional view showing the 90 connection between the feed-pipe and the branch feed-pipes. Fig. 12 is a fragmental, perspective view of the apparatus with the distributer lowered for work. The seat-stirrup and seat are broken away. 95

The usual hoops for the wooden tank are omitted for convenience of drafting.

1 is a heat-insulating tank which may be made of wood or other heat-insulating material, and is adapted to contain melted asphalt 100 and maintain the same at a temperature of approximately 200 degrees Fahrenheit, more or less, for a considerable length of time, thus to keep the material sufficiently fluid for several hours to allow distribution of all of the 105 same without liability of clogging the distributer as the charge in the tank becomes low. Said tank is mounted upon a suitable truck 2, the sills 3, 4 of the frame of which project rearwardly beyond the rear end of 110 the tank.

5 is a feed pipe provided with two branch

feed pipes 6 which are screwed into a tee 7 with a long threaded portion 8 so as to allow a limited rotation for swinging the feed pipes 6 up and down without any liability of leaking at the joint. The feed pipes 6 are each provided with a section 9 detachably connected thereto by a flanged joint 10 fastened by bolts 11 in the usual manner, so that the sections 9 may be detached from the main bodies of the feeders when that is desired. Said sections 9 form spaced inlets to a distributer-pipe 12 which is fixed to and carried by the feed-pipes, and is made of a straight tube having its ends closed by screw-threaded plugs 13.

14 is a valve-shell provided with and detachably or otherwise fixed to the distributer-pipe 12 by suitable hangers 15 fastened to the distributer-pipe 12 by suitable means, as screws 16. The hangers fit the distributer-pipe 12 liquid tight, and registering slotted passages 17, 18, are provided through the under-side of the distributer 12 and the top side of the hangers respectively, whereby liquid may flow into the shell from the distributer-pipe 12. The shell 14 has a cylindrical bore, the ends of which are stopped by plugs 19 removably screwed thereinto.

20 designates rotary valve-sections which in the form shown are three in number, each formed of a tube fitted liquid-tight in the bore of the shell 14 and provided on the upper side with longitudinal slots 21 of approximately the same length as, but of greater width than the slots 18 of the hangers, so that each section 20 may be rotated throughout a considerable arc without closing communication between the distributer-pipe 12 and the interior of such valve-section. The under side of each valve section is provided with outlets 22 in the form of a row of perforations which are of less diameter than the width of the slots 21, and are adapted to register with a corresponding row of outlets 23 extending along the bottom of the shell.

24 designates arms having screw-threaded portions 25 and extending respectively through circumferential slots 26 in the rear side of the valve-casing 14. Said screw-threaded portions 25 are respectively screwed through the inner valve sections 20, thus affording substantial means for partially rotating the rotary valve-sections 20 respectively.

55 The purpose of providing three valve sections 20 within the valve-shell is to enable the operator to control the flow of the liquid from the distributer at three separate sections thereof, so that in practical operation 60 when the apparatus is moving along a street and all of the valve sections are turned to the open position, a sheet of liquid 27 equal in width to the length of the three valved sections 20 will be allowed to flow from the 65 valve and spread over the ground; and if it is

desired, the middle section may be adjusted to shut off the flow of liquid while the two end sections are allowed to be open; or, one of said end sections may be closed while the other is open. In this way any or all of the 70 three sections may be employed as desired. The perforations 22 in the valve sections are of such size relative to the distance they are spaced apart that when liquid flows out through the outlets 23 the several streams 75 will run together, thus spreading the liquid over the ground evenly along the full line of each section, and the thickness of the stream from any section may be regulated by moving the arm 24 to an appropriate position for 80 that purpose. When said arm 24 is fully depressed the perforations 22, 23 will be fully opened, and the same may be closed by gradations through the upward movement of the arms 24. The arms 24 are operable by 85 links 28 and bell-crank-levers 29. Each of said levers 29 terminates in a handle 30 at the middle of the space between the rearwardly-projecting sills 3, 4, to be in ready reach of an operator mounted on a seat 31 carried by a 90 stirrup 32 that is mounted on said sills 3, 4.

33 designates a windlass mounted in bearings 34 on the sills 3, 4, and provided with a hand-wheel 35 between said sills, whereby the windlass may be rotated to wind flexible 95 connections as chains 36 which are connected with the distributer-pipe 12 by links 37 and pivot bearings 38 to which the links are pivoted by detachable pivots 39.

40 designates a ratchet device to hold the 100 windlass stationary to support the swiveled distributer pipe, and its connections. The links 37 are mounted to slide up and down between guide pins 41 and engage the opposite sides of the sills 3, 4 to prevent displacement of the distributer relative to the truck frame.

The swiveled distributer is supplied from the tank through the usual tank valve 42, which is connected by a rod 43 with a lever 110 44 carried by a standard 45 on said tank and operated by a line 46 which swings down into reach of the operator for manual operation from the seat 31.

In practice, the apparatus is to be operated by two persons, a driver seated on the usual driver's seat, not shown, at the front of the vehicle, and an operator seated on the operator's seat 31, at the rear of the machine; said operator's seat being located at a suitable height rearwardly of the distributer pipe, which may serve as a foot-rest for the operator. When the operator is in position on the seat 31, the levers 29, hand wheel 35, ratchet 40, and valve line 46 are 115 all within his reach for manual operation from said seat.

When it is desired to transport the road oiler without distributing oil or asphalt, the operator will throw the valve levers 39 for 120 125 130

ward, to close the distributor valve outlets, and will allow the tank valve 42 to close. Then he will turn the hand wheel 35 of the windlass 33, thus winding up the connections 36, thereby drawing the swiveled distributor pipe and its valve, up out of the way. When he desires to begin the operation of oiling he will grasp the hand wheel, loosen and release the ratchet 40 and lower 10 the swiveled distributor pipe from the position in Fig. 1 to that shown in Fig. 12, and he will adjust one or more of the levers 30 to position to turn one or more of the valve sections to position to open the outlet from 15 the valve case. He may then open the valve 42 as desired, and the oil will flow from the tank into the distributor-pipe and into the valve-case, passing through each rotary-valve-section that is open, and escaping 20 through the valve-case at the outlet thereof. In the meantime the driver will drive the vehicle over the road, street, or other ground to be oiled, and the operator will regulate the discharge of the oil, asphalt, or other 25 material to be distributed, by manipulating the handles 30.

The insulating tank serves the double purpose of preventing discomfort to the driver on account of the heat of the asphalt, 30 and of retaining the heat of the asphalt so as to maintain said asphalt in liquid condition.

The vehicle frame 47 is spring-supported by the springs 48 shown in Fig. 1 thus to prevent injury to the distributing appliances 35 from jolts and jars that might otherwise be destructive or injurious.

It is not necessary that the valve sections tightly fit the tubular bore of the valve-case or shell, for the reason that when the valve 40 is closed the weight of the liquid pressing downward upon the valve-section tends to hold the valve tightly closed and to prevent any leakage therefrom, and this is the case where the valve-sections are loosely fitted 45 in the bore; the only precaution necessary being that the lower portion of the valve-section when closed shall conform to the portion of the shell upon which it rests.

The construction whereby the distributor-pipe is controlled by tubular valve-sections 50 gives great strength of parts, and security against disalignment or disarrangement of the valve is done away with.

What I claim is:—

55 1. The combination with a truck, springs mounted on the truck and a heat insulating tank mounted on the springs, of a vertical feed-pipe leading downwardly from the tank; a tee at the lower end of the feed-pipe, 60 branch feed-pipes extending transversely from the tee, elbows upon the outer ends of the branch feed-pipes, pipe-sections extending backwardly from the elbows, the joints between the pipe-sections and the tee being loose enough to allow the pipe-sections to 65 swing up and down; a distributing-pipe connected to the rear ends of the pipe-sections, and means carried by the truck for raising and lowering the distributing-pipe.

2. A tank, a feed-pipe leading from the tank, a distributor-pipe connected to the feed-pipe, a valve-shell connected to and parallel with the distributor-pipe and provided with outlets, there being a series of ports extending along and leading from the distributor-pipe into the valve-shell, a valve-tube rotatably mounted in the valve-shell and provided with a series of inlet and outlet ports arranged therealong so that by rotating the valve-tube the flow from the distributor-pipe through the valve-tube is regulated, and so that when the valve-tube is set at any position to open the outlets the discharge through all of said outlets will be practically uniform as to volume and velocity.

3. A truck, a tank mounted on the truck, a feed-pipe extending from the tank, a distributor-pipe connected to the feed-pipe and mounted horizontally and transversely of the line of travel, means for moving the distributor-pipe up and down, a valve-shell extending the length of the distributor-pipe and connecting therewith and provided along said shell with a series of outlets, and means for simultaneously regulating said outlets by opening or closing the same.

4. A truck, a tank mounted thereon, a feed-pipe extending downwardly from the truck, a tee at the lower end of the feed-pipe, 100 branch-pipes extending horizontally from the tee transversely of the line of travel, elbows at the outer ends of the branch-pipes, pipe-sections extending backwardly from the elbows, the joints between the pipe-sections and the tee being loose enough to allow the pipe-sections to swing up and down, a distributor-pipe connected to the rear ends of the pipe-sections, and a windlass carried by the truck and connected to the distributor-pipe for raising and lowering the same.

5. A distributor-pipe provided in its lower side with slots, a valve case fastened thereto and provided with slots corresponding to and registering with the slots of the distributor-pipe, and being provided with a peripheral slot and with outlets, a tubular valve-section in said valve-case and provided with outlets to register with the outlets of the case in one position of the valve, and to close said outlets at another position of the valve, and provided with a slot of greater width than and registering with the inlet slot of said case, and an arm through said peripheral slot and screwed into said valve-section to turn the same.

6. A distributor-pipe provided with outlet slots, a valve-case provided with hangers and with a slot to register with the outlet slots of said distributor-pipe, and also pro-

vided with an outlet, said valve-case being fixed to the distributer-pipe, a tubular valve in said valve-case, and means for rotating said tubular valve to open and close said 5 outlet.

7. A distributer-pipe provided with outlet-slots, a valve-casing extending the length of the distributer-pipe and having ports communicating therewith, a tubular valve 10 in said valve-casing and having inlet and outlet ports forming passages transversely through the valve, there being slots in the valve-casing, and a handle connected to the tubular valve through said slots so that 15 by operating the handle the valve is operated to control the flow from the distributer-pipe through the valve.

8. A pipe provided with slots, means to supply liquid to said pipe, a valve case fastened to said pipe and provided with slots 20 registering with the slots of the pipe, and also provided with outlet perforations and with plugs in its ends, a plurality of tubular

sections in said case provided with outlets to register with the outlets of the case and also 25 provided with slots to register with, and wider than, the slots of the case, said case being provided with peripheral slots, and arms connected with said valve-sections and extending through said peripheral slots to 30 rotate said sections.

9. A road-oiler provided with a swiveled distributer, a rotary valve to control said distributer, a support fastened to the frame of the oiler rearwardly of the distributer, and 35 manual means operable from said support to raise and lower the distributer and to operate the valve means thereof.

In testimony whereof, I have hereunto set my hand at Los Angeles, California, this 14th 40 day of December 1907.

CHARLES ARTHUR BALDWIN.
